UNITED STATES PATENT OFFICE

124,075

DESIGN FOR A COMBINED SUPPORT AND CONTAINER FOR PERFUME

Herman Jacob, St. Paul, Minn., assignor to Stuart Products Company, St. Paul, Minn., a corporation of Minnesota

Application April 19, 1940, Serial No. 91,772

Term of patent 3½ years

To all whom it may concern:

Be it known that I, Herman Jacob, a citizen of the United States, residing at St. Paul, county of Ramsey, and State of Minnesota, have invented a new, original, and ornamental Design for a Combined Support and Containers for Perfume, of which the following is a specification, reference being had to the accompanying drawing, forming part thereof.

bined support and containers for perfume, showing my new design.

Figure 2 is a side elevational view.

I claim:

The ornamental design for a combined support
and container for perfume, as shown.

HERMAN JACOB.
